UNITED STATES PATENT OFFICE

LOUIS ROSEN, OF JACKSONVILLE, FLORIDA

COLLAR STIFFENER AND NECKTIE SUPPORTER

Application filed May 28, 1931. Serial No. 540,715.

The invention relates to a wearing apparel collar stiffener and necktie supporter and has for its principal object the provision of a device of the character stated that is made of two counterpart members adapted to be separately attached in the edge seams at the two ends of the collar to stiffen the collar flaps, and provided with an integral V-shaped member to engage under the fold of the collar to hold the collar shaped or supported, and having the extremities of the members curved and adapted to be entwined behind the necktie knot to support the knot shaped as well as holding the flaps of the collar in position.

The invention will be described in detail hereinafter and will be found illustrated in the accompanying drawings in which

Figure 1 is a fragmentary view of a shirt and collar and necktie, the collar being shown partly broken away, the collar stiffener and necktie supporter being shown applied thereto,

Figure 2 is a view similar to Figure 1 with the collar flaps and the necktie turned upwardly to disclose the position of the collar stiffener and necktie supporter,

Figure 3 is a view of the two members of the device,

Figure 4 is a top plan view of one of the members, and

Figure 5 is a side view in elevation of one of the members.

In the drawings similar reference characters are used to designate corresponding parts in all of the views.

The device consists of two counterpart members designated 1 and 2 respectively, and each of them provided with a sharpened pin portion 3 that is adapted to be inserted through the fabric of the collar flap as shown at 4 in Figure 2, A designating the collar. The pins 3 are located in the seam *a* in the end of the collar as shown in Figures 1 and

2. The members 1 and 2 are provided with V-shaped portions 5 having a side 6 that is substantially at right angles to the pins 3, and a portion bent from the part 6 in the V-shape on substantially the same plane as the portion 6 and designated 7, and then

bent upwardly as shown at 8, said V-shaped portions 5 being adapted to seat under the fold at *a'* of the collar A as clearly shown in Figure 1. At the ends of the portions 8 the members 1 and 2 are bent downwardly and curved as shown at 9, and when in position as shown in Figures 1 and 2 of the drawings, the parts 9 are entwined to hold the two members 1 and 2 together, and also to engage behind the knot *b* of the necktie B and to support said knot, the ends 9 being curved toward one another as well as toward the necktie as disclosed in Figures 3 and 5 respectively.

What is claimed is:—

1. A collar stiffener and necktie supporter, comprising counterpart members having pins to engage in the edge seams of collar flaps, V-shaped portions extending from said pins to fit under the fold of the collar remote from said edge seams, and curved extensions from said V-shaped portions in the direction of the pins adapted to entwine behind a necktie knot to support it.

2. A collar stiffener and necktie supporter, comprising counterpart members made of strands of wire, each strand having an end providing a pin adapted for insertion in the edge seam of a collar flap, a portion of said strand bent at substantially a right angle to said pin to engage in the collar fold, a second portion of the strand returned at an acute angle to said last mentioned portion on a line substantially at a right angle to the pin, then bent away from the pin at an obtuse angle to the second portion, and its extremity bent in the direction of the pin and curved, the curved extremities being adapted to entwine and provide a supporter for a necktie knot.

In testimony whereof I affix my signature.

LOUIS ROSEN.
